UNITED STATES PATENT OFFICE.

JAMES A. PARENT, OF DETROIT, MICHIGAN, ASSIGNOR OF ONE-HALF TO THOMAS S. RICHARD, OF DETROIT, MICHIGAN.

GAS-PRESSURE-REDUCING DEVICE.

1,377,970.

Specification of Letters Patent. Patented May 10, 1921.

Application filed May 14, 1920. Serial No. 381,497.

To all whom it may concern:

Be it known that I, JAMES A. PARENT, a citizen of the United States of America, residing at Detroit, in the county of Wayne and State of Michigan, have invented certain new and useful Improvements in Gas-Pressure-Reducing Devices, of which the following is a specification, reference being had therein to the accompanying drawings.

This invention relates to a gas regulating device commonly known as a "gas saver," and the primary object of my invention is to furnish a gas pipe or other conduit with a novel form of baffle which will tend to retard the velocity of gas therethrough and consequently reduce the pressure to such a degree as to produce a saving of gas and better ignition at a burner.

Another object of my invention is to provide a gas conduit with a series of articulated baffles providing a tortuous or sinuous passage for gas in the conduit, the baffles being disposed so as to prevent excessive pressure at an outlet, and in consequence of such baffles it is impossible for gas to flow through meters and into burners at a greater rate than can be recorded or used. In the first instance, it is possible to provide a desired number of baffles to reduce pressure of gas a desired degree whereby a meter of limited capacity could be installed on a high pressure gas line. In the second instance, it is a well known fact that various types of burners cannot be adjusted for excessive gas pressures, so my baffles may be installed to properly regulate the pressure of gas for a burner so as to insure proper combustion at the burner.

A further object of my invention is to provide fluid baffles for conduits with the baffles constructed to insure a thorough commingling of the products of combustion, and also to prevent displacement of the baffles by gas pressure within the conduit.

The above and other objects are attained by a mechanical construction that will be hereinafter specifically described and then claimed, and reference will now be had to the drawings, wherein—

Figure 1 is a longitudinal sectional view of a gas conduit provided with baffles which coöperate in producing a unitary result;

Fig. 2 is a cross sectional view taken on the line II—II of Fig. 1;

Fig. 3 is a perspective view of an initial or 55 conical pressure reducing member, and

Fig. 4 is a perspective view of a secondary or disk pressure reducing member.

As showing a conventional form of gas conduit, the reference numeral 1 denotes a 60 pipe having one end thereof connected by a sleeve 2 to an adjoining pipe 3, and the opposite end of the pipe 1 has a conventional form of union connection 4 with a pipe 5. The connections or couplings 2 and 4 permit of the pressure reducing member being easily installed within the pipe 1, and reference will first be had to the initial 65 pressure reducing member associated with the coupling 4 and shown in Fig. 3. The 70 initial pressure reducing member comprises a cone 6 having its large end provided with a peripheral flange 7 and this flange may be seated against the end of the pipe 1, within the coupling 4, with the small end of the 75 cone 6 extending into the pipe. The flange 7 will prevent the pressure of gas from shifting a cone within the pipe 1, and when the gas impinges against the converging 80 walls of the cone the gas is more or less 85 baffled so that its flow is somewhat retarded and its pressure reduced. Mounted in the large end of the cone 6 and axially thereof is a small cone 8 which is supported by opposed arms 9 having the ends thereof soldered or otherwise connected to the walls 90 of the cones 6 and 8. The cone 8 differs from the cone 6 by having its inner end completely closed so that said cone will provide a pocket and positive baffle for gas entering the same. When the gas is retarded by the cone 8, it will be necessary for the gas 95 to flow over the edges of the cone to enter the cone 6 and the restriction or reduced passage between the cones 6 and 8 is sufficient to further retard the gas as it enters the large cone or conical member 6.

The secondary pressure reducing member 100 comprises a series of spaced disks 10 having diametrically opposed edges thereof notched, as at 11, to receive parallel arms 12 which may be soldered or otherwise fixed relative to the disk so that the same will be maintained in spaced relation. Ends of the arms 12 may be bent, as at 13 so as to form 105 lugs which may be anchored between the ends of the pipes 1 and 3, within the sleeve or coupling 2 and with the arms so held it

is practically impossible for gas impinging against the disk to dislodge the member within the pipe 1.

The peripheral edges 10 of the disk are 5 notched or cut away, as at 14 and one side wall of each notch bent outwardly from the plane of the disk to form a deflector 15. With each disk having a single notch and deflector and no two notches in longitudinal 10 alinement, it is obvious that gas must travel in a sinuous path through the pipe 1 and when encountering the deflectors 15 a whirling motion will be imparted to the gas tending to further retard its passage through the 15 chambers formed between the disk 10 within the pipe 1. The gas in seeking its passage through the secondary pressure reducing member will have its pressure reduced and when this secondary pressure reducing 20 member is associated with the initial or conical pressure reducing member previously described, it is practically impossible for an excessive pressure of gas to pass through the pipe 1 and consequently there will be a 25 saving of gas and better ignition regardless of the nature of gas passing through the pipe. As natural gas is more active or volatile than artificial gas it may be only necessary to increase the number of disks 10 to 30 compensate for the activity of the gas. Under some conditions it may be only necessary to use the initial gas pressure reducing member, or even the secondary pressure reducing member by itself, but the best results 35 have been attained by using the members as shown in Fig. 1. Both of the pressure reducing members may be made of light and durable metal that will not corrode or deteriorate due to any moisture within the gas,

and since no alterations are required whatsoever in the conduit, it is obvious that the members may be easily and quickly installed. 40

I would have it understood that the size and shape of the pressure reducing members may be varied, and that any desired 45 number of said members may be employed to attain a desired reduction in gas pressure.

What I claim is:—

1. Means for reducing gas pressure within 50 a conduit composed of joined pipes, comprising parallel arms having end lugs clamped between the joined pipe ends of said conduit, and a series of disks carried by said arms and having notched edges with some of said notches accommodating said 55 arms and other of said notches providing a tortuous passage from one disk to another.

2. The combination with a conduit composed of joined pipes adapted to have gas pass therethrough, of a cone open at one end 60 only and supported axially of said conduit and providing a baffle, a cone surrounding and supporting the first mentioned cone, adapted to receive gas therefrom and restrict the passage of gas to the axis of said 65 conduit, a series of disks within the conduit adjacent the last mentioned cone causing the gas to travel in a tortuous path impinging against the walls of the conduit, and means 70 between joined pipe ends of said conduit preventing longitudinal displacement of said disks.

In testimony whereof I affix my signature in the presence of two witnesses.

JAMES A. PARENT.
